RECIPROCATING LEADING EDGE FOR AIR-FOILS AND HYDROFOILS

Alfred M. Caddell, 1318 W. Hunting Park Ave., Philadelphia 40, Pa.

Filed Sept. 25, 1958, Ser. No. 763,361

2 Claims. (Cl. 244—130)

This invention aims to speed airfoils and hydrofoils through air and water respectively by minimizing the resistance offered by their passage through these media. By providing reciprocal cutting edges for sustaining surfaces, the shape of fuselages or boat hulls may be altered to take advantage of such increased speed potential. When prefaced by dynamic instead of static leading edges, wings have increased carrying capacity and are capable of achieving exceptionally fast forward flight, while a dynamic hydrofoil fitted to a water craft also offers outstanding advantages to both air and water transportation.

Clearly, the faster a craft travels through air or water the greater, relatively, becomes the density or opposition of the media being penetrated. In water, the effect is increased resistance to its displacement. In air, the compressibility factor resulting from an aircraft's attack against the velocity-created air wall introduces both resistance and shock wave phenomena, the concussionary effects of which often spread to all parts of the craft. Vibrations are set up, resulting in harmonics that generate ever-increasing amplitudes or resonant swings, the effects of which may induce metal fatigue and disintegration of a craft.

As a means for attaining present-day speeds, thin wings, swept-back wings which impart a draw-knife effect on the air, or wings with fixed knife-edge leading edges are relied upon to accomplish the desired effect. Also, rivets have been countersunk, fairings and fillets contoured and skin surfaces polished to lessen resistance to travel of a craft through air.

But these developments do not go far enough toward minimizing the resistance or the shock wave problems generated. Both airfoils and hydrofoils perform at only half of their possible efficiencies due to the foil itself being inert, motionless and devoid of superior attack ability. But when altered to impart reciprocal cutting motion, the same airfoil or hydrofoil will penetrate air or water with practically half the effort otherwise required to attain a desired speed of travel therethrough.

In air travel, as a craft's speed increases, the compressibility or solidity of the air likewise increases, not in direct proportion but as the square of the speed. As evidence of this, the table of head resistances computed on the basis of .0032 pound resistance per square foot of plate set at a right angle to the wind (sea level pressure—Engineers' Unit Coefficient) gives a resistance of 32 pounds per square foot when hit by a 100-mile-per-hour wind; at 500 miles per hour 800 pounds and at 1,000 miles 3,200 pounds.

In calculating the performance of an aircraft on the drawing boards, engineers reduce all frontal dimensions to approximate the square feet of surface offered to the wind and attempt to arrive at the total resistance in pounds that should be encountered at any specified altitude and speed. On the basis of such calculations, a plane traveling at a speed of 600 miles per hour at sea level and having a total of 10 square feet of penetrating area will be confronted with the enormous drag of 11,520 pounds of head resistance; which drag will of course continue to increase as the square of the speed as forward relative velocities mount higher. This resistance poundage is based, as aforesaid, on resistances offered at an altitude where atmospheric pressure is great-

2

est and accounts for jet planes seeking higher flight altitudes.

In the case of jet powered craft wherein the faster it travels the more efficient jet propulsion becomes, the attainment of supersonic flight speeds becomes the paramount goal. Whereas the gas being discharged from a jet's tail pipe has a speed of approximately 1,227 miles per hour, the highest flight speed attained in level flight at sea level is about 550 or 600 miles per hour or roughly, 50 percent of the jet or slipstream speed. The lost 50 percent is consumed by resistance offered in the craft's passage through the air. Translated into operating statistics, this means that fully half the craft's possible flight range, pay load and fuel costs are, at present, needlessly sacrificed.

It is that staggering loss which this invention aims to lessen and thus make possible greater speeds per pound of thrust put out by an engine. Militarily, the value of increased flight efficiency is incalculable.

In wind tunnel tests conducted by this applicant, resistance readings of a fixed wing were taken at various angles of mounting and at various air speeds, after which readings were taken on an identically formed wing having a reciprocating leading edge. A D.C. motor was faired between a right and a left wing and an adjustable, cam-operated arm permitted controlled reciprocal motion of the leading edge. The travel extended from 1 to 2 inches on each side of center. When the 2-inch motion was employed the motor shaft turned at 1,110 r.p.m.; at 1-inch travel it was operated at 1,850 r.p.m. A scale was installed to measure the differences in drag between the fixed wing and that registered for the wing carrying the reciprocating leading edge.

These tests pointed the way for attaining 40 to 50 percent reductions in drag. The greatest gain occurred with the 1-inch travel at a motor shaft speed of between 1,600 and 1,800 r.p.m. With two reciprocal movements per shaft revolution, the cutting motions thus registered between 3,200 and 3,600 per minute. Translated into lift-drag ratios, the results indicate that a wing having an average 20-1 ratio could be enlivened to nearer a 40-1 ratio if fitted with a leading edge given high reciprocal motion, thus converting the major portion of the thrust now lost in the slipstream to increased forward speed at no further demand of thrust output.

In other fields of activity, when one desires to penetrate or cut anything, such as a log of wood or a loaf of bread, the cutting edge is not just pressed downwardly through the log or bread in the manner that wing surfaces are pushed through the air. Rather the entering edge of the tool is given reciprocal motion. By the name token the same basic cutting law, at present neglected, is extremely applicable to airfoils and hydrofoils for efficient air and water penetration.

Considerable experimentation has been conducted in the latter field. Vessels have been equipped with hydrofoils comprised of thin, ladder-like strips of metal attached in vertical tiers to the hull of a boat. During forward motion, the hull rises on the hydrofoils until, virtually free of water drag, it speeds along on the bottom-most foils. Reciprocal cutting edges fitted to these same hydrofoils would lessen the resistance they now offer in penetrating the water, thus increasing over-all efficiency.

In the drawings:

FIG. 1 is a partial view, looking downward, of the reciprocating leading edges of wings, showing a source of power in the form of an electric motor embodied in the body of a craft and twin cams connected thereto, one for reciprocally actuating one leading edge and the other to operate the leading edge of the opposite wing.

FIG. 2 is a frontal, partial cross sectional view of the

leading edges showing their extreme outboard reciprocal travel, while

FIG. 3 is a similar view showing their extreme inboard travel. The two inner arrows at the bottom thereof depict the extent of travel of these leading edges, while the two outer arrows indicate the inboard overhang of the leading edges.

FIG. 4 is a three-quarter view showing part of an airplane wing and its reciprocating leading edge mounted in position thereupon; also, the top access hole covers of the leading edge and the ball bearings that permit high-speed, anti-frictional reciprocal movement of said leading edges.

FIG. 5 shows the bow outline of a boat outfitted with underwater hydrofoils equipped with reciprocating leading edges.

FIG. 6 is a three-quarter fragmentary view of an airplane showing each of the wing surfaces fitted with a reciprocating edge.

FIG. 7 is an enlarged view showing divided stub shaft 14 with its ball construction 14A intermediate coupling 15 for permitting adjustability of the reciprocal travel of the leading edges and connection of this shaft with the slave rings of cams 9 and 10.

These leading edges are comprised of walls having a shell-like construction consisting of top 1, bottom 2, forward knife-edge 3 and reinforcing sections 4, which are integrated with the top and bottom walls on their inner sides as shown particularly in FIG. 4. Spar 24 contains several recessed areas which carry grooveways 6, as shown in dotted outline in FIGS. 1 and 4. Bearings 5 are mounted in said reinforcing sections, said bearings extending approximately half way into these grooveways. These bearings are also shown in dotted outline in grooves 6, FIG. 1. They maintain spatial alignment with the spar and permit anti-frictional reciprocal travel of the shell construction relative to the fixed position of the spar. A number of openings are formed in the top and bottom walls of said shell construction to permit access to the interior thereof. Removable covers 7 of these openings, illustrated only on the top of the shell, are flushingly secured thereto by a plurality of screw bolts 8.

These shells may be given cutting motion by any conventional means. Obviously, the right and left shells are separate entities and in minimum travel are separated from each other by a space as at 1B. As shown herein, cams 9 and 10, which are rotated by motor 11, cause two cutting motions per revolution of shaft 12. Both these cams are mounted eccentrically, the apexes thereof facing opposite to each other on said shaft, to which they are keyed, as at 13. Outer slave rings 9A and 10A respectively of these cams follow their eccentric motions. Connected to rods 14, these slave rings transmit movements of their respective cams through adjustable couplings 15. Stub shafts 22, which have a socket construction 22A for partially encompassing ball-like structure 14A of rods 14 are secured to walls 20 of the shells, as shown in FIGS. 1, 2, 3 and 7.

Rods 14 have threads which engage threaded coupling 15, shown in detail in FIG. 7. This permits fine reciprocal travel adjustment of the leading edges. Locknuts 21 of couplings 15, shown clearly in FIG. 7, secure the settings of rods 14.

Knife-edge 3 is formed at the extreme forward position of the shell construction by the merging of the top and bottom walls thereat. Also, the top and bottom surfaces have tapering overlapping sections 1A and 2A re-

spectively at their trailing edges to minimize drag as the reciprocating edges cut their way through the fluid media.

Grooveways 6 may be given a polished surface to minimize drag movement of ball bearings 5 therein. These grooveways are secured to spar 24 by a plurality of screw bolts 17, shown in dotted outline in FIGS. 1 and 4.

The airfoil, or wing, rearwardly of the reciprocating leading edge, is indicated by 16, which may be applicable to either airfoil or hydrofoil construction. In conjunction with spar 24, 16 may constitute a sustaining means for either an aircraft or a marine vessel. Double-headed arrow 18, shown at the bottom of FIG. 3, indicates the minimum extent of the reciprocal travel of both the shell-like leading edges, while double-headed arrow 19 indicating the maximum extent of travel thereof.

Double-headed arrow 25 indicates the extent of maximum travel of each shell, double-headed arrow 26 the extent of up-travel and arrow 27 the down-travel of the cams, thereby establishing their eccentric orbit.

Numerical 23 indicates the hull of a conventional boat riding in the water, the hydrofoils previously mentioned being shown in a cutaway section of said water, and the actuating means therefor being shown in dotted outline at the bottom of the boat's hull. The operative action of the hydrofoils is similar to that of the airfoils.

Having described my invention, I claim:

1. In a craft having a body and sustaining surfaces for supporting said body in fluid media, powered means for moving said body through said media, a forward and a trailing end of said surfaces and an expanse of surface area therebetween, said forward end having a forwardly projecting spar formed to comprise a top, a bottom and a tapered forward edge, recesses provided in the top and bottom of said spar and a number of half-circle grooveway formations secured therein, walls comprising a cambered shell construction shaped to spatially envelop said spar and to provide a movable leading edge therefor, a trailing edge formed on the top and on the bottom of said shell construction, said trailing edge extending rearwardly relative to said leading edge and over-hanging said expanse of surface to provide a top and bottom extension therefor, said shell having reinforced sections positioned opposite said recesses, a plurality of half-circle formations in said reinforced sections and bearings positioned therein and protruding therefrom to occupy said grooveways, means for affording access to the interior of said construction, a source of power in said body and means connecting said source with said shell for imparting oscillatory travel motion thereto.

2. The structure as described in claim 1 wherein said cambered shell is connected to said source of power by adjustable means for varying the oscillations of said shell and the extent of reciprocal travel thereof relative to the fixed position of said spar.
